UNITED STATES PATENT OFFICE.

BURNSIDE E. SAWYER, OF ATHOL, MASSACHUSETTS.

DRAWING-BOARD.

SPECIFICATION forming part of Letters Patent No. 435,980, dated September 9, 1890.

Application filed June 11, 1890. Serial No. 355,011. (No model.)

To all whom it may concern:

Be it known that I, BURNSIDE E. SAWYER, of Athol, in the county of Worcester and State of Massachusetts, have invented certain new and useful Improvements in Drawing-Boards, of which the following taken in connection with the accompanying drawings, is a specification.

This invention relates to drawing-boards, and has for its object the construction of a drawing-board that can be more readily and easily kept true; and it consists in certain novel features of construction, arrangement, and combination of parts which will be readily understood by reference to the description of the drawings and to the claims hereinafter given, and in which my invention is clearly pointed out.

Figure 1 is a plan of my improved drawing-board. Fig. 2 is a horizontal section of a portion of the drawing-board at the upper left-hand corner of Fig. 1. Fig. 3 is a similar section of a portion of the drawing-board at the lower left-hand corner of Fig. 1. Fig. 4 is a vertical section through a portion of the board on line 1 1 on Fig. 2. Fig. 5 is a partial vertical section on line 2 2 on Fig. 2. Fig. 6 is a partial vertical section on line 3 3 on Fig. 2. Fig. 7 is a partial vertical section on line 4 4 on Fig. 3. Fig. 8 is a partial vertical section on line 5 5 on Fig. 3. Figs. 9, 10, and 11 are respectively a side elevation and end view and a transverse section of the eccentric adjusting-pin for connecting the movable end of the pivoted bar to the fixed bar, as will be more fully described.

In the drawings, 'A' is the main body of the drawing-board, made, preferably, of well-seasoned soft-pine wood, and having formed in two at least of its edges rectangular grooves extending the whole length of the sides or ends in which they are formed, and also having formed in its upper side a rabbet *a*, extending along one side and across one end, as shown.

A T-shaped metal bar *B*, having its central rib *b* cut short at one end and having secured thereto at said shortened end the two plates *b'* *b''* by screws or rivets so as to project beyond the end of said shortened rib and form a fork, is permanently secured to one edge of said board, with its central rib in said

groove, by screws *c c*, as shown in Figs. 1, 3, and 8. To the opposite edge of the board *A* is secured in like manner a short section of 55 a similar T-shaped bar *D*, having its central rib *d* shortened and the plates *d'* and *d''* secured thereto, as shown in Figs. 2, 4, and 5. To the fork of the bar *D* is pivoted at *e* one end of the T-shaped metal bar *E*, the central 60 rib *e'* of which enters the groove in the end of the board *A* and has formed in the end thereof opposite to the pivot *e* an open slot *e''* to receive the eccentric neck *g* of the adjusting-pin *F*, which is mounted in bearings 65 in the plates *b'* and *b''*, which form the fork of the bar *B*.

The pin *F* has formed in its end a slot to receive a screw-driver for turning it about its axis when it is desired to adjust the bar *E*. 70

The bars *B* and *E* have their faces planed and ground to perfectly straight and true surfaces, and the inner faces of their upper ribs *b''* and *e''* are planed so as to be substantially of an even thickness, as shown. 75

The rabbets *a a* formed in the corners of the board *A*, together with the inner faces of the ribs *b''* and *e''*, form grooves in the upper surface of the board, which are intended for use in connection with another invention of 80 mine—viz., an improved T-square—which forms the subject-matter of another application of even date herewith.

All drawing-boards made of wood are subject to changes occasioned by changes in temperature or in the humidity of the atmosphere, and it is seldom that a board swells or shrinks to exactly the same extent at both ends, and as a consequence such boards have to be trued up by a wood-workman quite often. 85 9c

My invention obviates the necessity of taking the boards to the carpenter or joiner's shop every time it is found out of square, for by simply turning the eccentric-pin one way or the other the bar *E* can be adjusted till it 95 is found to be accurately at right angles to the bar *B*.

I claim—

1. A drawing-board having a metal bar secured to one of its edges in a fixed position, 100 and a second metal bar secured to another edge at right angles to the first bar, said second bar being connected at one end to the board by a hinge-joint and at its opposite

end by an eccentric-pin, whereby said second bar may be readily and accurately adjusted relative to the first-named bar.

2. In a drawing-board, the combination of 5 the main body of the board made of wood or other suitable material, and having two of its edges grooved and rabbeted along its upper corner, a metal bar of T shape in cross section secured in a fixed position to one edge of 10 said main body with its central rib in the groove of said main body, so as to form a rectangular groove between the metal and wood along the upperside of the board, and a second bar of metal of like cross-section attached to 15 another edge of said board at right angles to the first-mentioned metal bar by a hinge or pivotal connection at one end, and at its other end by means of an eccentric adjusting-pin, in position to form a rectangular groove be- 20 tween the metal and wood along its upperside.

3. In combination with the main body of

a drawing-board, the T-shaped bar having its central or horizontal rib shortened at one end, and having secured thereto upon each side a short plate, which extends beyond the 25 shortened rib to form a fork, said plates having formed in said projecting ends circular openings or bearings, a pin set in said bearings and having its middle portion reduced in size and made eccentric to its end portions, 30 and a second T-shaped bar having a slot formed in one end of its central or horizontal rib to receive the eccentric neck of the pin.

In testimony whereof I have signed my name to this specification, in the presence of 35 two subscribing witnesses, on this 7th day of June, A. D. 1890.

BURNSIDE E. SAWYER.
